UNITED STATES PATENT OFFICE

112,145

DESIGN FOR A BEVERAGE DISPENSING CABINET

Herman H. Harr, East Cleveland, Ohio

Application June 16, 1938, Serial No. 77,860

Term of patent 14 years

To all whom it may concern:

Be it known that I, Herman H. Harr, a citizen of the United States, residing at 1116 Eddy Road, in the city of East Cleveland, county of Cuyahoga, and State of Ohio, have invented a new, original, and ornamental Design for a Beverage Dispensing Cabinet, of which the following is a specification, reference being had to the accompanying drawing, forming a part thereof.

I claim:

The ornamental design for a beverage dispensing cabinet, substantially as shown.

HERMAN H. HARR.
